FORM FOR MAKING LATEX ARTICLES

Abraham N. Spanel, Dover, Del.

Application November 29, 1937, Serial No. 176,949

12 Claims. (Cl. 18—41)

This invention relates to forms for producing deposited, flat, seamless latex articles.

In the production of large flat latex articles, prior to the present invention, it has been necessary to use large flat forms. These forms, due to their size were difficult to handle. Large dipping tanks were needed to accommodate the forms and consequently a large amount of latex was also necessary. All of these factors added to the cost of production of the articles. Another problem was encountered when it was desired to furnish the articles in a variety of colors. For each color, a large batch of latex had to be compounded and additional dipping tanks had to be provided.

Accordingly, the purpose of the present invention is to produce these articles on forms that are very much smaller than the length of the article or its width, or both, thereby making possible the use of very much smaller tanks and greatly reduced quantities of specially colored liquid latex.

Another important advantage in the present invention is that the smaller forms make possible quicker dipping time by virtue of their reduced size, and also much easier handling in removing the deposited film of latex from the form.

It is an object of this invention to provide a form on which a flat latex article such as an apron, can be made, said form being approximately one-half as large as the forms heretofore necessary in the production of an article of like size, and having a single continuous surface on which the apron or the like may be made by the deposition of latex thereon.

It is another object of this invention to provide a pocket forming means on a form to generate an integral pocket in the article deposited thereon.

These and other objects and advantages of the invention will appear from the detailed description and claims when taken with the drawings in which:

Fig. 1 is a plan view of an apron made in accordance with the present invention;

Fig. 2 is a plan view of one face of a form on which the article of Fig. 1 may be made.

Fig. 3 is a plan view of the opposite face of the form shown in Fig. 2.

Fig. 4 is an edge view of the form shown in Figs. 2 and 3;

Fig. 5 is a vertical section taken on line 5—5 of Fig. 2;

Fig. 6 is an enlarged fragmentary sectional 55

view of the form shown in Figs. 2 and 3, showing a coating of latex applied to the form;

Fig. 7 is a section taken on line 7—7 of Fig. 4, showing a coating of latex applied to the form;

Fig. 8 is a section taken on line 8—8 of Fig. 4, showing a coating of latex applied to the form;

Fig. 9 is a fragmentary sectional view taken on line 9—9 of Fig. 2 and illustrating the manner in which latex is deposited on the pocket-forming portion of the form;

Fig. 9A is a fragmentary portion of Fig. 9 illustrating a slightly modified construction;

Fig. 10 is a plan view of a blank from which the form of the present invention may be made;

Fig. 11 is an edge view of the blank shown in Fig. 10 after it has been folded in accordance with the method of the present invention;

Fig. 12 is a vertical section through a blank illustrating a modified manner of forming the upper margin of the form;

Fig. 13 is a fragmentary plan view of a still further modified form;

Fig. 14 is an edge view of the form shown in Fig. 13, and

Fig. 15 is a vertical section of the form shown in Fig. 13 taken on line 15—15 of that figure.

Referring to Fig. 1 of the drawings, 5 indicates a seamless deposited apron comprising a bib portion 6 and a body portion 7 provided with an integral pocket 8. An opening 9 is formed in the upper end of the bib portion 6 to receive the neck of the wearer while the integral tie-strings 10 may be tied around the waist of the wearer. It will be noted that each of these tie-strings as deposited, extend upwardly toward the neck portion of the apron in order to reduce the necessary size of the form on which the apron is deposited. However, if the tie-strings 10 were left in the condition shown in Fig. 1, the apron

40 might present an insufficiently attractive appearance. In order to obviate this disadvantage, openings 11 are provided in the apron adjacent the junction of the tie-strings 10 with the apron proper. The free end of each tie-string can be

45 inserted in its related opening 11 and the entire tie pulled therethrough. As a result of this operation, the tie-strings are permanently held in a downwardly extending position. All free edges of the apron are preferably reinforced by thickened deposits of latex integral with the apron as will appear hereinafter.

As mentioned above, if the apron 5 were made on a flat form, of a size equal to that of the apron in its normal shape, a relatively large dipping tank would be required. In order to reduce

the size of the dipping tank with a consequent reduction of the amount of latex and to facilitate handling of the forms themselves, applicant has provided the novel form 15 shown in Figs. 2 and 3 which is approximately one-half as large as the article deposited thereon.

In its preferred construction, the form 15 comprises a blank 16 (Fig. 10) folded on itself as shown in Fig. 11 to provide two flat sections 17 and 18 joined by a curved section 19, and having their adjacent surfaces spot welded together. The blank 16 as well as the marginal strips and various plates to be hereinafter described are preferably made of aluminum or stainless steel although any other material to which latex will removably adhere, may be used.

Raised borders 20 are provided at the end edges of the curved section 18. As shown in Fig. 7, each border 20 comprises one flange of a bendable metal strip 21 having therein a longitudinally extending groove 22 which engages the edge of the curved section of the blank. The strips may be soldered or otherwise secured to the blank. The other flange 23 of each strip 21 provides a support for the sealing plates 24 which are preferably soldered to the flanges 23. In addition to sealing the curved portion of the blank and thereby prevent latex from entering therein when the form is immersed in latex, these plates carry the form-supporting arms 25 which are adapted to be mounted on a suitable dipping rack (not shown).

The opposite vertical edges of the flat sections 17 and 18 are also provided with longitudinally grooved strips 26 each having flanges 27 which project from each surface of the flat sections and like borders 20 terminate in an abrupt edge for a purpose to be described. The groove in each of these strips is wide enough to snugly receive the superposed edges of the two sections. The strips are preferably soldered to the blank and in addition to forming a raised border for the form surfaces, hold the edges of the blank in contacting relation. The upper end 28 of each strip 26 is mitered so that the flanges thereof form a continuation of the border 20 on the curved section of the form. The lower end of each strip stops short of the bottom of the form as shown at 29 in Figs. 2 and 3. It will be noted in Fig. 10, that the rounded corners of the blank 16 have been cut inwardly of the longitudinal edges of the blank as indicated at 30, so that the article-defining wall 31 of the flanges 27, which project inwardly of the edge of the blank, will merge with the rounded corners of the completed form. The lower end of the form between the ends of the strips 26 is defined by the abrupt edges 32 as shown in Figs. 2, 4 and 5. A plate 33 having straight edges 34 which together with the adjacent flanges 27 define the tie-strings 10 of the apron, is secured in spaced relation to each side edge of the section 18. The curved edges 35 of the plate 33 define the outline of the bib portion 6 of the apron while a circular raised plate 36 secured to the section 18 in symmetrical spaced relation to the plate 33 defines the neck opening 9 in the apron bib. Studs 37 projecting from the bib forming surface of the form define the small reinforced apertures 11 at the junction of the tie-strings 10 with the apron proper.

If desired, a pocket 8 may be formed integrally with the apron by soldering or welding one end of an angular piece 38 to the form surface. The side edges and lower end 39 of the piece 38

are rounded to avoid abrupt edges, since an abrupt edge would generate a thin or weakened section in the latex deposited thereon. The junction of the piece 38 with the form surface may be smoothly rounded as at 40 to avoid the accumulation of a thickened deposit of latex at this part if so desired, or the junction may be abrupt, as indicated at 40a in Fig. 9A, where a reinforced region is desired at the junction. 10 While the pocket forming element 38 has been shown as applied to the body forming section 17 of the apron form, it will be understood that the invention is not limited to this particular location since the element could be applied to the opposite face of the form if it were desired to provide a pocket in the bib portion of the apron.

The broken lines in Fig. 10, represent the relative positions of the various elements on the blank before the same is folded. The plates 33 and 36, and pocket forming piece 38 may be secured to the blank either before or after the blank is folded.

In use, the form 15, is preferably coated with latex by dipping it into a latex bath in the following manner, although it is to be understood that the form may be coated by spraying or the like, if desired. The form, supported from a suitable dipping rack (not shown) by means of the arms 25, with the abrupt edge 32 lowermost, is immersed into a tank of latex and then withdrawn therefrom. The latex will be uniformly deposited on the flat and curved surfaces of the sections 17, 18 and 19 as a layer 41. However, at the recesses defined by the borders 20 and the adjacent surface of the curved section 19 the latex will accumulate as a thickened reinforcing ridge 42 as shown in Fig. 7. Since the border terminates in an abrupt corner or edge 43 a thin or weakened line will be developed in the layer of latex at this edge whereby the article may be readily trimmed. Latex will similarly accumulate at the recesses defined by the flanges 27 to provide a reinforced margin for the body portion and one margin of the tie-strings of the apron, as shown at 44 in Fig. 8. At the abrupt edge of the flanges 27 a thin or weakened section will be developed in the latex layer permitting easy separation of the waste latex deposited over the outer surface of the strips 26, from the reinforced edge 44 of the apron. Since the plates 33 and 36 project abruptly from the form surface to define recesses with the adjacent surface of the form, latex will accumulate therein as a reinforcement for the margins defined by these plates, as shown at 45 in Figs. 6 and 8. As in the case of the flanges 20 and 27, a weakened section will be developed in the latex deposited on the abrupt corners of the plates whereby the latex deposited on the surfaces of these plates may be readily separated from the reinforced margins 45. Immediately above the lower abrupt edges 32 of the form the latex will accumulate as a reinforcement which in section is semi pear-shaped as shown in applicant's copending application, Serial No. 740,141, filed August 16, 1934. As illustrated in Fig. 6 the latex will be deposited as a substantially uniform layer 46 over the pocket forming member, which layer will be integral with the layer 41 deposited on the section 17.

The form may be dipped as many times as necessary to develop an apron of desired thickness. The apron may be vulcanized on the form or after it has been stripped therefrom. If de-

sired a prevulcanized latex may be used in which case the layer of deposited latex need only be dried.

In Fig. 12 there is shown a blank 50 for producing a modified form 15. The blank 50 has one edge preferably beveled as at 51 and is folded back on itself as at 52 whereby the opposite faces 53 of the blank are joined by the smooth curve of the folded portion 52. It will be understood that the junction 54 may be soldered or otherwise finished to avoid a recess in which latex could accumulate as a thickened deposit. Except for this difference the form will be of the same construction as that described above. The completed form will be used in the same manner as the previously described form 15.

In Figs. 13 to 15 applicant has illustrated a still further modified construction. A cylindrical member 60 which corresponds to the curved portion 19 of the form 15, is provided with a slot 61 in which is seated one edge of a plate 62. The recess defined by the surface of the plate 62 and the adjacent surface of the member 60 is provided with fillets 63, which may be of solder or the like to prevent latex from accumulating therein. Each of the side edges of the plate 62 are provided with a grooved strip 64 similar to strip 26 applied to the form 15. A plate 65 of greater diameter than the cylindrical member 60 is secured to each end of the cylindrical member 60, so that a flange 66 projecting a slight distance beyond the curved surface of this member is provided at each end thereof. It will be understood that the faces of the forms illustrated in Figs. 12 and 13 will be provided with raised plates such as the plates 33 and 36 on form 15, in order to generate tie-strings and a neck opening in the article deposited thereon and may also be provided with a pocket forming member such as 38 at any desired point on the form to generate an integral pocket in the deposited article. These forms may be used in the same manner as set forth in detail in the description of form 15.

While the invention has been described particularly with reference to an apron, and to the forms and to the method of making the forms for producing an apron, it will be understood that the invention is not to be limited by the detailed description, since many modifications, variations and adaptations will occur to those skilled in the art. These modifications, variations and adaptations are to be considered as falling within the scope of the invention as defined by the following claims.

What I claim is:

1. A form on which an article may be made by depositing rubber thereon, comprising a flat section, a transversely curved section extending along one margin of said flat section, the opposite surfaces of said flat section being joined by the curved surface of said curved section, reinforcement-generating means disposed along opposite edges of said flat section and the opposite ends of said transversely curved section, and article-outline defining means on at least one surface of said flat section.

2. A form on which an article may be made by depositing rubber thereon comprising a plate, an elongated substantially straight cylindrical member having a groove therein, one edge of said plate being seated in said groove, article-reinforcement-generating means disposed along at least a portion of the margin of said plate and the ends of said cylindrical member.

3. A form on which an article may be made

5 by depositing rubber thereon comprising a member made of sheet material, folded on itself to provide a flat section and a substantially straight portion rounded in cross section, disposed along one margin of the flat section, the opposite surface of said flat section being joined by the rounded surface of said portion, reinforcement-generating means disposed along the edges of said rounded portion and along a portion of the remaining margins of said flat section.

4. A form on which an article may be made by depositing rubber or the like thereon, comprising a plate-like section, a substantially straight elongated portion, curved in cross section, extending 15 along one margin of said plate-like section, the curved surface of said portion joining the opposite surfaces of said plate-like section, reinforcement-generating means on said portion and the plate-like section to define a portion of the margin of the article deposited thereon.

5. A form on which an article may be made by depositing rubber or the like thereon, comprising a plate-like section, a substantially straight elongated portion, curved in cross section, extending 20 along one margin of said plate-like section, said portion being thicker than said plate-like section and the curved surface thereof smoothly joining the opposite surfaces of said plate-like section, reinforcement-generating means on said portion and the plate-like section to define a portion of the margin of the article deposited thereon.

6. A form on which an article may be made by depositing rubber or the like thereon, comprising a member made of sheet material folded 25 along a substantially central line thereof to provide a curved section and a flat plate-like section, said flat plate-like section comprising superposed portions of said sheet material having their adjacent surfaces in contact with each other, the opposite surfaces of said plate-like section being joined by the surface of said curved section, means on the opposite faces of said plate-like section for generating marginal reinforcements for the article deposited thereon.

7. A form on which an article may be made by depositing rubber or the like thereon, comprising a plate-like section, a rounded border at one edge of said plate-like section having its surface merging with the opposite surfaces of said plate-like section, means on one surface of said plate-like section for developing a neck-receiving opening in the article deposited thereon and means on said last-mentioned surface for defining tie strings in said article.

55 8. A form on which an article may be made by depositing rubber or the like thereon, comprising a sheet-like member having an abrupt edge at one end, a substantially straight enlarged, transversely curved section at the opposite end 60 smoothly joining the opposite surfaces of said sheet-like member, and means on said form for supporting the same with the abrupt edge lowermost.

9. A form on which a sheet-like article having a pocket integral therewith may be made by depositing rubber or the like thereon, said form having a surface for generating a sheet-like article, and a pocket-generating plate having one edge thereof secured to said surface, the remainder of said plate being spaced from said surface.

10. A form on which a sheet-like article having a pocket integral therewith may be made by depositing rubber or the like thereon, said form having a surface for generating a sheet-

like article, and an angular plate having one edge thereof secured to said surface, the remainder of said plate being spaced from said surface, the remaining edges of said plate being rounded in cross-section.

11. A form on which an article having a pocket integral therewith may be made by depositing rubber or the like thereon, said form having an article-generating surface, and a pocket-forming plate having one edge thereof secured to said article-generating surface, the remainder of said plate being spaced from said surface, the junction of the surfaces of said plate with said article-generating surface being abrupt to provide a recess in which a thickened deposit of the rub-

ber or the like will be accumulated to provide a reinforced region in the resulting article.

12. A form on which an article having a pocket integral therewith may be made by depositing rubber or the like thereon, said form comprising a plate-like section, a transversely curved section extending along a margin of said plate-like section, the opposite surfaces of said plate-like section being smoothly joined by the curved surface of said curved section, and a pocket-generating plate having one edge thereof secured to one of said surfaces of said form, the remainder of said plate being spaced from said form.
